CLAIM

The ornamental design for a dental appliance set, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top front perspective view of a lower appliance showing the new design;

FIG. 2 is a top rear perspective view thereof;

FIG. 3 is a bottom front perspective view thereof;

FIG. 4 is a bottom rear perspective view thereof;

FIG. 5 is another rear perspective view thereof;

FIG. 6 is a top front perspective view of an upper appliance showing the new design;

FIG. 7 is a top rear perspective view thereof;

FIG. 8 is a bottom front perspective view thereof;

FIG. 9 is a bottom rear perspective view thereof; and,

FIG. 10 is another rear perspective view thereof.

1 Claim, 10 Drawing Sheets
